RICHARD H. RYNE, OF NEW YORK, N. Y., ASSIGNOR TO WILLIAM S. HICKS, OF SAME PLACE.

Letters Patent No. 72,684, dated December 24, 1867.

IMPROVEMENT IN PEN AND PENCIL-CASES.

The Schedule referred to in these Letters Patent and making part of the same.

TO ALL WHOM IT MAY CONCERN:

Be it known that I, RICHARD H. RYNE, of New York, in the county of New York, and State of New York, have invented certain new and useful Improvements in Pen and Pencil-Cases; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in the construction of a combined pen and pencil-case, in which the case proper consists of a single length of tube, with a reversible pen-holder, having a screw-pencil in its opposite end.

Figure 1 is a side elevation, with the pen ready for use.

Figure 2 is a side elevation of the pen-holder detached, with the pencil represented extended, in red.

Figure 3 is a side view, having a portion of the case broken away, and with the holder reversed, representing the pencil ready for use; and

Figure 4 is a longitudinal section of the pen-holder, representing the pencil drawn in.

In constructing my improved device, I form the case A of a single length of tube, of metal, or any other suitable material, and provide the top with a screw-cap, B, as shown in the drawings. Within the tube A, I place a small disk, of cork, leather, rubber, or similar material, as represented by e of fig. 3, which is capable of being moved up or down, as may be desired, but which is held in place by the pressure of its periphery against the inside of the tube A, this disk thus forming a bottom to a small chamber in the upper end, to hold the lead-points. By making the chamber thus, instead of the usual way, I accomplish two objects: first, if the pen should happen to be too long for the case, the disk e can be moved up, and thus afford more room for it, the leads, if necessary, being broken for this purpose; second, by making the disk e of soft or flexible material, like cork or rubber, and movable, the points of the pen, if they happen to hit against it, will not be injured, as they would be if it were made of metal, and stationary. It is obvious, however, that instead of this flexible and movable disk, a stationary one may be used in making the case, if desired. I then construct the pen-holder proper, of a short tube, C, within which I secure an ordinary screw-pencil, a, in such a manner that by holding the part c, and turning the part f, the pencil-point, a, can be screwed out or in at pleasure, the part c being attached to the screw-tube of the point, within the tube C, as shown in fig. 4; there being a bead, o, formed on the exterior of the tube C, which limits the distance that C may be inserted into the case A, so that the part c will protrude, as shown in fig. 3. When thus arranged, the device has the appearance of an ordinary screw or pocket-pencil, and by taking hold of the protruding part c, and turning the case or handle A, the pencil-point a can be run out or in at pleasure. Within the opposite end of C, I secure a head, n, leaving a space between it and the tube C, into which a pen may be forced and held securely, as shown in figs. 1 and 2, the head n being soldered or otherwise secured to the upper end of the screw-tube, as shown in fig. 4.

To use the pen, the holder C will be reversed in the case A, as represented in fig. 1, but when the pen is not to be used, then the holder C will be turned and inserted, as shown in fig. 3, the pencil then being where it may be extended ready for use at any moment, without reversing the holder. By this construction I produce a combined pen and pencil-case, that is very light, cheap, and compact, and that is well adapted to the twofold purpose or use as a desk and pocket-pen and pencil, it being much less cumbersome, and better adapted to the purposes of writing than the double or extension-cases.

Having thus described my invention, what I claim, is—

A combined pen and pencil-case, consisting of the case A and the reversible pen-holder C, having a screw-pencil point, a, arranged therein, substantially as shown and described.
